(Cl. D48—20)

To all whom it may concern:

Be it known that I, David M. Morgenstern, a citizen of the United States, residing at Euclid, in the county of Cuyahoga and State of Ohio, have invented a new, original, and ornamental Design for a Portable Spotlight, of which the following is a specification, reference being had to the accompanying drawing, forming part thereof.

In the drawing

Fig. 1 is a rear elevational view of a portable spotlight showing my new design;

Fig. 2 is a side elevational view of the spotlight;

Fig. 3 is a front elevational view of the same; and

Fig. 4 is a bottom plan view thereof.

I claim:

The ornamental design for a portable spotlight, as shown.

DAVID M. MORGESTERN.
